BASKETBALL PASSING IMPROVEMENT SHIELD

Jack Richard Cordier, 1465 Whittlesey Ave.,
Atwater, Ohio

Filed Oct. 23, 1962, Ser. No. 72,238

Term of patent 14 years
(Cl. D34—5)

FIG. 1

FIG. 2

The opposite side of this design is plain.

I claim:

The ornamental design for basketball passing improvement shield, as shown and described.
